UNITED STATES PATENT OFFICE.

JOHN CLINTON WRIGHT, OF ROCHESTER, NEW YORK.

APPARATUS FOR TREATING PHOTOGRAPHIC FILMS.

1,158,615.

Specification of Letters Patent. Patented Nov. 2, 1915.

Application filed April 12, 1915. Serial No. 20,855.

To all whom it may concern:

Be it known that I, JOHN C. WRIGHT, a citizen of the United States, residing at Rochester, in the county of Monroe and State 5 of New York, have invented certain new and useful Improvements in Apparatus for Treating Photographic Films, of which the following is a specification, reference being had to the accompanying drawings.

10 My invention relates to photographic apparatus, and particularly to apparatus for treating photographic films.

The primary object of my invention is the provision of means for supporting a 15 film in connection with a bath tray either for developing or fixing the film, and providing means for carrying the film into the bath tray and out again, this means keeping the film in a suspended position so that 20 every portion of the film will be subjected to the bath.

A further object of my invention is the provision of means adapted to support the ordinary photographic tray, and also provided with a belt, bands, or other flexible connection adapted to be connected to a film, and so connected to a winding drum or roller that as the drum or roller is wound up the film will be passed from one end to 30 the other through the bath.

A still further object of the invention is to provide a film supporting member of the character above described, so constructed that the parts may be readily disassembled 35 and folded up into compact form for ready transportation.

Other objects will appear in the course of the following description.

40 My invention is illustrated in the accompanying drawings, wherein:

Figure 1 is a side elevation of my film treating mechanism, the base being in section; Fig. 2 is a fragmentary end elevation; Fig. 3 is a section on the line 3—3 of Fig. 1.

45 Referring to these figures, 2 designates a base which is provided at its opposite ends with the pulleys or rollers 3 and 4. This base has an area sufficient to support upon it a tray or tank 5 adapted to contain a fixing 50 or developing solution. Extending upward from the base 2 at opposite ends thereof, are the uprights 6 which are provided at their

upper ends with rollers or pulleys 7 and 7^a. Mounted upon one of these uprights by means of hinged brackets 8 is a winding 55 drum or roller 9.

Extending upward on the inside face of one of the uprights 6 and over the roller or pulley 7 is a cord, belt, or other flexible connection 10, which, at one end, is adapted to 60 be attached to a film clip 11. This band 10 passes over the roller 7 and thence downward on the exterior face of the corresponding upright 6, and passes over a roller 3. Thence the band passes beneath the hollow 65 base to and over the roller 4 and thence upward, and around the winding drum 9. A flexible connection 10^a passes from the drum 9 upward and over the roller 7^a, the extremity of this band being also provided with a 70 clip or other film engaging means, designated 12. Preferably the ends of the film 13 are held by means of clips, the clips being provided each with a perforation through which hooks 14 are engaged. 75

Preferably, and in order to provide for the disassembling of the parts and provide for the parts being folded into compact form, I make the uprights 6 in two sections, these sections being connected by a hinged 80 joint 6^a, and I also form the lower end of the lower section with downwardly projecting prongs or pins 15 which may be inserted in suitable perforations 16 made in the base, these perforations being disposed on each 85 side of the rollers 4. The base is cut away at 17 so as to permit the passage of the flexible connection 10 beneath the rollers 4 and between the face of the base plate. The face is mounted on feet 2^a to support the 90 rollers in spaced relation to the table.

While I do not wish to limit myself to any specific manner of supporting the winding roller 9, I preferably hinge the brackets 8 to the corresponding upright 6, each of these 95 brackets being formed with a perforation for the passage of a winding shaft 19. This shaft 19 is split for a portion of its length, as at 20, and provided with the transverse pin 23 and with a crank handle whereby the 100 shaft may be rotated. The winding drum 9 has a central passage to accommodate the shaft 19, and is also formed with the transversely extending pin 21, which is received

in the kerf or slot 22 in the shaft. After the shaft is inserted in place in the perforation of the brackets 8, the pin 23 is passed through the shaft holding the drum firmly 5 in place.

While I do not wish to limit myself to the use of any specific form of flexible element, I preferably use a thin ribbon of tape about a quarter of an inch wide.

- 10 The operation of my invention will be obvious from the above description. The ends of the film are connected to the clips 11 and 12. The winding drum 9 is then rotated in one direction so that one end of 15 the film, that for instance engaged by the clip 11, will be disposed above the bath. The winding drum is then rotated so as to lower this end of the film into the bath and then raise it from the bath. By a continuous 20 motion of the winding drum the film is lowered into the bath, carried through the bath and again raised, and then by reversing the rotation of the winding drum the film may be again carried into the bath and 25 therethrough and then raised out of it.

It will also be obvious that the film may be carried through the bath in either direction any number of times, and that a very uniform motion or speed may be maintained 30 so that every portion of the film will be submitted to an equal action of the bath. Thus one portion of the film will not be left in the bath any longer than any other portion. Furthermore, the film may be 35 kept in the best possible condition for use and prevented from becoming folded. The same apparatus may be used for either developing the film, fixing the film, or giving it the washing necessary between the developing or fixing operations by simply removing or placing the tray.

It is obvious that my invention may be modified in many ways without departing from the principle thereof, and that it is 40 very simple, and that it is effective for the purpose intended.

While I have illustrated a winding drum 9 upon which the flexible connection is wound, it will of course be understood that 45 other means for securing a reciprocation of the flexible connection might be used and that I do not wish to limit myself to winding the flexible connection around the drum.

Having thus described my invention, what 50 I claim is:

1. In an apparatus for treating photographic films, a base adapted to support a receptacle, uprights on each side of the base, rollers mounted upon the uprights, a flexible connection passing over said rollers and having at its ends means for engaging a film, and means for shifting the flexible connection in one direction or the other to

thereby carry the film supported thereby in one direction or the other through said receptacle. 65

2. In a device for treating photographic films, a base adapted to support a bath receptacle, said base having a transversely extending passage, uprights mounted upon the base, rollers mounted upon said uprights, a winding drum operatively supported with relation to the base, rollers disposed upon the base at the ends of the passage, and a band engaged by said winding drum passing beneath the rollers in the base and through said passage and then extending upward over rollers at the upper end of the uprights, and means carried at the ends of the band for detachably engaging a film. 70 75 80

3. A device for treating photographic films comprising a tray supporting base, and means mounted upon the base for detachably engaging the opposite ends of a film and drawing said film back and forth 85 through a bath supported upon said base.

4. A device for treating photographic films comprising a bath tray supporting base, and means mounted upon the base for detachably engaging the opposite ends 90 of a film and drawing said film back and forth through the bath supported upon said base, said means including a flexible connection to which the ends of the film are connected detachably, and means having 95 winding engagement with the flexible connection for operating it.

5. A device for treating photographic films comprising a base adapted to support a bath tray, uprights mounted upon the base, a flexible connection passing over said uprights and across the base, means mounted upon one of the uprights for giving a reciprocating movement to the flexible connection, and film engaging clips detachably 105 mounted upon the ends of the flexible connection.

6. A device for treating photographic films comprising a base adapted to support a bath tray, uprights detachably mounted 110 upon the base, rollers mounted upon the upper ends of the uprights, supporting arms hingedly mounted upon one of said uprights, a winding drum disposed between the said arms, a detachable shaft passing 115 through the arms and through the drum, rollers mounted upon the base, and a flexible connection passing over said winding drum, one end of the connection passing over one 120 of the first-named rollers, the other end being passed beneath the rollers on the base, then upward over the roller carried on the uprights, and then downward, said flexible connection having means on its extremities for engagement with the film. 125

7. A device for treating photographic

films comprising a base adapted to support a bath tray, uprights formed of hinged sections detachably mounted upon the base, a flexible connection passing over said uprights and across the base, means detachably mounted upon one of said uprights for operatively engaging the connection and adapted to give a reciprocating motion

thereto, and film engaging means carried by the ends of the flexible connection.

In testimony whereof I hereunto affix my signature in the presence of two witnesses.

JOHN CLINTON WRIGHT.
